BOOKKEEPING DEVICE

William Theodore Maass, Chicago Heights, Ill.

Application March 18, 1950, Serial No. 150,413

8 Claims. (Cl. 282—26)

1

This invention relates to a bookkeeping device, and relates particularly to such a device wherein superposed record sheets may be easily aligned with a transfer means therebetween and held in a holder which maintains this alignment.

In making bookkeeping entries on a plurality of record sheets at the same time, it is necessary that these sheets be properly aligned so that the entry will be made on one line of the top sheet and transferred by means of carbon paper or the like to the desired line on the next sheet when the sheets are arranged in superposed relationship. When the record sheets are, for example, a ledger and a journal, the single entry must be made on one line of the ledger and on another line of the journal. Subsequent entries may then be made on the following lines. Ordinarily these simultaneous entries on several record sheets are made by using a bookkeeping machine. For the small business man, however, these bookkeeping machines are too expensive and thus he usually makes each entry separately.

I have invented a bookkeeping device wherein superposed sheets may be easily aligned in a desired relationship with a carbon paper or other transferring means inserted therebetween and the superposed sheets arranged in a holder or posting folder for maintaining this alignment and permitting the insertion of the sheets and the holder into an ordinary typewriter. Thus a single entry made by using the typewriter will appear on the desired lines of each of the superposed sheets.

Various efforts have been made in the past to solve this problem of providing the proper alignment of sheets and holding them in this alignment for insertion into a typewriter. These prior methods and devices have not been too successful, however, as they were either too complicated for daily use, were easily broken so as to be unserviceable, or permitted the sheets to get out of alignment while they were being inserted in the typewriter.

In the bookkeeping device of this invention, I provide a record sheet, such as a ledger sheet, having a vertical row of spaced holes in each side margin of the sheet, with each lateral pair of holes located at the ends of a section on the sheet adapted to receive writing and bearing indicia at one end of these section. There is also provided a second sheet having similarly spaced sections bearing indicia on each end thereof so that these indicia are visible through the holes of the first sheet when the first sheet is placed over the second sheet. As the indicia on the

2

second sheet are visible through these holes, perfect alignment of a given section on one sheet with a given section on the other sheet may be obtained. I also provide a holder in which the superposed sheets are held to maintain the alignment. This holder includes holding means on at least one margin embracing corresponding portions of the superposed sheets. A transfer means, such as a piece of carbon paper, is provided between the sheets so that an entry made on the top sheet will be simultaneously transferred to the second sheet. With this arrangement the proper alignment may be readily secured and the entries may be made either by writing by hand or the record sheets and the holder may be inserted in a typewriter. The holder maintains the alignment of the sheets during this insertion and while the device is held in the typewriter.

20 In the preferred construction, the first record sheet is provided with a pair of vertical rows of holes at each side margin with a hole of each row being aligned with a hole of each of the other rows and located at the ends of a section on the sheet that is adapted to receive writing. Each of these sections bear indicia, such as numbers, spaced inwardly of the pairs of vertical rows of holes. The second record sheet is provided with similar spaced sections bearing indicia, such as numbers, on each end of these sections so that the numbers are visible through one row of holes on opposite sides of the first sheet when the first sheet is placed over the second sheet. This permits ready alignment of a given section on one sheet with a given section on another sheet preparatory to making simultaneous entries thereon. The second sheet is provided with a row of holes on opposite sides thereof, with each hole aligned with an indicium and registering with the other row of holes on the first sheet when both sheets are properly aligned. The holder in which the superposed sheets are held to maintain this alignment is provided with a side flap overlying the rows of holes on the corresponding sides of the first sheet, with this flap being provided with a pair of rows of holes. One of these rows registers with said one row of holes on the first sheet to permit viewing the indicia on the second sheet. The row of holes of the flap registers with the said other row of holes in the first sheet and a row of holes in the second sheet. Indicia are provided on opposite sides of the holder spaced similarly to the indicia on the first and second sheets. This holder indicia are visible through one of said other rows of holes on

the other sheet, the corresponding row of holes in the second sheet and said other row of holes in the flap when the sheets are properly aligned in the holder. The indicia on the first sheet are located inwardly of the flap so as not to be hidden thereby. A piece of carbon paper is arranged between the sheets to serve as a transfer means.

In order to aid further in aligning the superposed sheets in the holder, this holder is preferably provided with a top flap overlying a corresponding portion of at least one of the record sheets and provided with a plurality of spaced holes. This one sheet bears contrasting sections appearing through these holes when the sheets are properly aligned in the holder. Each of these contrasting sections is of substantially the same size and shape as its corresponding hole.

In one form of the device, the carbon paper is permanently attached to the underneath side of the top sheet. In another embodiment, this carbon paper is separate, but is fixed preferably at the top edge to a holder which extends beyond the carbon paper and under the flap to permit proper positioning of the carbon paper, but prevent any of the paper from extending under the side flap.

The invention will be described as related to the embodiment shown in the accompanying drawings. Of the drawings: Fig. 1 is a front elevation of the holder of this invention with the top and side flaps extended; Fig. 2 is an elevation partially broken away of an assembly of a ledger sheet, a journal sheet and transfer means therebetween properly positioned within a holder or posting folder; Fig. 3 is a section taken along line 3—3 of Fig. 2; Fig. 4 is a fragmentary section taken along line 4—4 of Fig. 2; and Fig. 5 is a fragmentary elevation of an alternate embodiment of the carbon paper having a holder attached thereto.

The holder or posting folder 10, shown in the accompanying drawings, is preferably a rectangular sheet of heavy paper having a flap 11 extending across the top thereof and a second flap 12 extending down one side, preferably the left hand side, of the holder. These flaps 11 and 12 are adapted to be folded over on the rectangular portion of the holder 10, as shown in dotted lines in Fig. 1. The top flap 11 is provided with a pair of spaced holes or openings 13. The side flap 12 is provided with a pair of substantially parallel rows of holes, as indicated at 14. The record sheets, shown in the accompanying drawings, include a first sheet 15 which may be a ledger sheet and a second sheet 16 which may be a journal sheet. The first sheet 15 is provided with a side flap 17 adapted to extend around the corresponding side of the second sheet 16, as shown in Fig. 3. The first sheet 15 is provided with a pair of rows of holes 18 on the edge thereof that is adapted to be arranged beneath the holder flap 12. These holes extend through the body of the first sheet and through the flap 17. The first sheet 15 is also provided with a pair of rows of holes 19 on the other side thereof. The first sheet 15 is provided with a row of indicia 20 such as numbers located adjacent the inner edge of the holder flap 12, but spaced inwardly thereof.

The second sheet 16 is provided with a row of holes 21 beneath the flap 12 and a second row of holes 22 on the opposite side of this second sheet. This sheet is provided with a row of indicia, as indicated at 23, that are visible through

the innermost row of holes 14 in the holder flap 12 and the innermost row of holes 18 in the first sheet 15. This second sheet is also provided with a row of indicia, as indicated at 24, and located inwardly of the row of holes 22 so as to be visible through the innermost row of holes 19 on the first sheet 15. The indicia in each row and the holes in each row are spaced apart equal distances. This spacing provides room for writing either by hand or by typewriter or other writing machine on the top sheet 15 which is transferred by a transfer means, such as a sheet of carbon paper 25, to the second sheet 16. Each of these first and second sheets is preferably lined with parallel lines, as indicated in Fig. 2, with the corresponding indicia and holes each being located substantially midway between adjacent lines.

When the first sheet 15, second sheet 16 and flap 12 on the holder 10 are arranged in the position shown in Fig. 2, the outermost row of holes 14 on the flap 12, the outermost row of holes 18 on the first sheet 15 and the row of holes 21 on the second sheet are all aligned so that the row of indicia 26 on the holder 10 will be visible therethrough. Similarly, the innermost row of holes 14 are aligned with the innermost row of holes 18 so that the indicia 23 on the second sheet 16 are visible therethrough. When proper alignment has been achieved, the indicia 24 on the opposite side of the second sheet 16 are visible through the innermost row of holes 19 on the first sheet 15, the indicia 27 on the opposite side of the holder 10 are visible through the aligned holes 22 in the second sheet 16 and the outermost holes 19 in the first sheet 15.

As can be seen in Fig. 1, the indicia in the rows 26 and 27 on the holder 10 are a series of numbers beginning with 1 at the top of the holder and progressing consecutively down both sides of the holder. With this arrangement, the numbers in any transverse line are the same. The indicia 23 and 24 on opposite sides of the second sheet 16 are similar numbers arranged in the same order. In the rows 23 and 24 of the second sheet the lines are numbered consecutively beginning at the top. The row of indicia 20 on the first sheet 15 are similar numbers and serve to number the lines consecutively on this sheet.

The top flap 11 of the holder 10 is provided with a plurality of spaced holes 13, here shown as two. These holes are adapted to be aligned with contrasting sections 29 on corresponding sections of either the first sheet 15 or the second sheet 16 when the sheets are properly arranged in the holder 10. Each of these contrasting sections which may be of a color different from that of the sheets 15 and 16 is of substantially the same size and shape as its corresponding hole 13.

In using the device of this invention for the simultaneous entry of a record on a plurality of record sheets, the desired line on the first sheet 15 and the desired line on the second sheet 16 are noted. The second sheet 16 is arranged beneath the first sheet 15 and the left hand edge of the second sheet is moved under the first sheet flap 17 until this edge reaches the fold between the flap 17 and the first sheet 15, as shown in Fig. 3. The two sheets are then moved longitudinally of each other until the number of the desired line on the second sheet appears through the corresponding hole in the innermost row of holes 18 and the corresponding hole in the in-

nermost row of holes 19. When these figures appear, the sheets 15 and 16 are properly aligned. As shown in Fig. 2, for example, line No. 5 on the second sheet 16 appears opposite line No. 1 on the first sheet 15. This indicates that an entry made on line No. 1 of the top sheet 15 will be made at the same time on the fifth line of the second sheet 16. Where subsequent entries of the same type are to be made, they will be entered on the following lines of the first sheet and will simultaneously be made on the following lines of the second sheet 16.

After the two sheets 15 and 16 have been thusly arranged, they are placed on the holder 10 and moved upwardly under the top flap 11 and to the left under the side flap 12. When the sheets are properly arranged in the holder, the contrasting sections 29 on the second sheet 16 will appear through the holes 13 in the top flap 11. These contrasting sections 29 are placed on both the first and second sheets 15 and 16 so that they will be visible through the holes 13 depending upon whether the top edge of the first sheet extends beyond the top edge of the second sheet or vice versa. In the arrangement shown, it is the second sheet 16 whose top edge extends above the corresponding edge of the first sheet so that contrasting sections 29 are seen on the second sheet.

When the superposed sheets 15 and 16 are properly positioned in the holder 10, the indicia or numbers 26 on the left hand margin of the holder will be visible through the left hand row of holes 14 in the flap 12. Similarly the right hand row of holes 27 on the holder 10 will be visible through the right hand row of holes 19 on the top sheet 15. Proper alignment is achieved when the same numbers in the rows 26 and 27 are located at the ends of a given line on the top sheet 15. Thus, the numbers in the rows 23 and 24 show when the sheets 15 and 16 have been properly aligned with respect to each other. The numbers in the rows 26 and 27 show when the sheets have been properly arranged in the holder. The contrasting sections 29 appearing through the holes 13 serve as a further check to show proper alignment of the sheets in the holder.

After record sheets 15 and 16 have been arranged in the holder, entries may be made on the top sheet 15 and transferred by means of the carbon paper 25 to corresponding lines on the second sheet 16. These entries may be made by handwriting, if desired. However, the device is particularly useful for insertion in an ordinary typewriter. When the device is inserted in the typewriter, the assembly of the first sheet 15, second sheet 16 and holder 10 is grasped firmly and the top edge of the device is inserted under the roller. The roller is turned until the top edge of the device comes within reach. The roller is then released and the sheets are grasped firmly at the top and pulled to the position for writing on the desired line. The roller is then reset and an entry is made by means of the typewriter on the desired line of the first sheet and simultaneously on the corresponding line of the second sheet. Additional entries of the same type may be made on subsequent lines of the two sheets without removing the sheets from the typewriter. When different record sheets are to be used, the device is removed from the typewriter, the desired sheets assembled in the manner stated above, and the device re-inserted in the typewriter. With this arrangement the alignment of the sheets may be easily checked

before the device is inserted in the typewriter and then rechecked after the device is in the typewriter to insure that the alignment has not been disturbed in inserting in the typewriter. The combination of the side flap 12 and the top flap 11 on the holder 10 normally prevents the sheets getting out of alignment during insertion in the typewriter.

In the embodiment shown in Figs. 2, 3 and 4, the carbon paper 25 is attached to the back of the first sheet 15 as by a gummed strip of paper 30. If desired, however, the carbon paper may be a separate piece 31 as shown in Fig. 5. In this embodiment, the carbon paper is preferably attached at its top edge to a reinforcing and mounting strip 32 having a projecting end 32a extending beyond the left hand edge of the carbon paper 31. This projecting end is substantially as long as the width of the holder side flap 12. With this arrangement, the carbon paper 31 is inserted between the sheets 15 and 16 with the outer end of the projecting end 32a located adjacent the fold between the flap 12 and the holder 10. This provides proper location of the carbon strip 31 so as to prevent it being inserted beneath the side flap 12. The left hand edge of the carbon paper will then be adjacent but beyond the free edge of the side flap 12.

If desired, instructions for using the device may be printed on the holder 10 between the parallel rows of numbers 26 and 27. Also, if desired, the side flap 12 and the sides of the sheets 15 and 16 may have printed thereon the description of the numbers which are to appear through the holes in these portions.

It is clearly evident that the bookkeeping device described herein may be of any size desired for use in typewriters having a standard carriage width or in machines having carriages wider than the standard machine. The record sheets may be of any type desired.

When the device is used for making entries by hand, standard spring clips may be used at the top and left hand edges of the device to retain the holder and the record sheets in the proper alignment. However, these clips are not required as with ordinary care the assembly may be held by pressure with one hand while the entry is being made.

In the embodiment shown in the drawings, the first sheet 15 is a ledger sheet containing the name of the account and the second sheet 16 is a journal sheet. Entries made on the ledger are immediately transferred to the journal. In the embodiment shown, the journal or second sheet 16 is provided with an extending portion 33 having two columns 33a and 33b providing debit and credit columns. This extending portion provides a separate journal with a ledger account for control accounts such as bank, sales, purchases or any other separations desired. The main portion of this sheet headed journal shows to which accounts the entries are debited or credited and the right hand side 33 shows debits or credits inversely. The sum of the debits on both sides must equal the sum of the credits on both sides and may be carried forward to succeeding pages. The forms shown, however, are given merely by way of example as it is obvious that any type of record sheets desired may be used.

Although in the illustrated embodiments holes are provided for alignment with the corresponding numbers, it is believed obvious that any form of transparent portions could be used.

Having described my invention as related to the embodiments set out herein, it is my intention that the invention be not limited by any of the details of description unless otherwise specified, but rather be construed broadly within its spirit and scope as set out in the accompanying claims.

I claim:

1. A bookkeeping device comprising a first record sheet having a vertical row of spaced holes at each side margin with each lateral pair of holes being located at the ends of a section on said sheet adapted to receive writing and bearing indicia at one end of said section; a second record sheet having similarly spaced sections bearing indicia on each end of said section so that the indicia are visible through said holes when the first sheet is placed over the second sheet to permit alignment of a given section on one sheet with a given section on the other sheet; a holder in which said superposed sheets are held to maintain said alignment, said holder including holding means on at least one margin embracing corresponding portions of said superposed sheets, said holder comprising a heavy paper sheet provided with a top flap overlying a corresponding portion of at least one of said sheets and provided with a plurality of spaced holes, said one sheet bearing contrasting sections appearing through said holes when said sheets are properly aligned in said holder, each of said contrasting sections being of substantially the same size and shape as its corresponding hole, and provided with a side flap overlying a corresponding portion of said sheets and provided with a row of holes spaced similarly to the holes in said first sheet for alignment with said first sheet holes and through which said indicia on said second sheet appear when said sheets are properly aligned and arranged in said holder, said indicia on said first sheet being located beyond said side flap.

2. A bookkeeping device comprising a record sheet having a pair of vertical rows of holes at each side margin with a hole of each row being aligned with a hole of each of the other rows and located at the ends of a section on said sheet adapted to receive writing, each of said sections bearing indicia spaced inwardly of the pair of vertical rows of holes; a second record sheet having similarly spaced sections bearing indicia on each end of said sections so that the indicia are visible through one row of holes on opposite sides of said first sheet when the first sheet is placed over the second sheet to permit alignment of a given section on one sheet with a given section on the other sheet, said second sheet bearing a row of holes on opposite sides thereof with each hole aligned with an indicia and registering with the other rows of holes in the first sheet when said sheets are properly aligned; a holder in which said superposed sheets are held to maintain said alignment, said holder having a side flap overlying said rows of holes on the corresponding side of said first sheet and provided with a pair of rows of holes, one row registering with said one row of holes of the first sheet to permit viewing the indicia on said second sheet and the other row registering with the said other row of holes in said first sheet and a row of holes in said second sheet, and indicia on opposite sides of said holder spaced similarly to said indicia on the first and second sheets, said holder indicia being visible through one of said other row of holes in the first sheet, the corresponding rows of holes in the second sheet and said other rows of holes in the flap when said sheets are properly aligned in said holder, said indicia on said first sheet being located inwardly of said flap, said holder comprising a heavy paper sheet provided with a top flap overlying a corresponding portion of at least one of said sheets and provided with a plurality of spaced holes, said one sheet bearing contrasting sections appearing through said holes when said sheets are properly aligned in said holder.

of holes in the flap when said sheets are properly aligned in said holder, said indicia on said first sheet being located inwardly of said flap; and a transfer means between said sheets.

3. The device of claim 2 wherein said holder comprises a heavy paper sheet provided with a top flap overlying a corresponding portion of at least one of said sheets and provided with a plurality of spaced holes, said one sheet bearing contrasting sections appearing through said holes when said sheets are properly aligned in said holder, each of said contrasting sections being of substantially the same size and shape as its corresponding hole.
4. The device of claim 2 wherein said transfer means comprises a carbon paper separate from either of said sheets and is mounted on a holder which extends beyond said carbon paper and under said flap.
5. The device of claim 2 wherein said first sheet is provided with a side flap adapted to embrace the corresponding edge of the second sheet for aid in aligning said sheets with respect to each other, and said pair of vertical rows of holes on the corresponding margin of said first sheet are aligned with similar holes in said flap.
6. A bookkeeping device comprising a record sheet having a pair of vertical rows of holes at each side margin with a hole of each row being aligned with a hole of each of the other rows and located at the ends of a section on said sheet adapted to receive writing, each of said sections bearing indicia spaced inwardly of the pair of vertical rows of holes; a second record sheet having similarly spaced sections bearing indicia on each end of said sections so that the indicia are visible through one row of holes on opposite sides of said first sheet when the first sheet is placed over the second sheet to permit alignment of a given section on one sheet with a given section on the other sheet, said second sheet bearing a row of holes on opposite sides thereof with each hole aligned with an indicia and registering with the other rows of holes in the first sheet when said sheets are properly aligned, said first sheet being provided with a side flap adapted to embrace the corresponding edge of the second sheet for aid in aligning said sheets with respect to each other, and said pair of vertical rows of holes on the corresponding margin of said first sheet are aligned with similar holes in said flap; a holder in which said superposed sheets are held to maintain said alignment, said holder having a side flap overlying said rows of holes on the corresponding side of said first sheet and provided with a pair of rows of holes, one row registering with said one row of holes of the first sheet to permit viewing the indicia on said second sheet and the other row registering with the said other row of holes in said first sheet and a row of holes in said second sheet, and indicia on opposite sides of said holder spaced similarly to said indicia on the first and second sheets, said holder indicia being visible through one of said other row of holes in the first sheet, the corresponding rows of holes in the second sheet and said other rows of holes in the flap when said sheets are properly aligned in said holder, said indicia on said first sheet being located inwardly of said flap, said holder comprising a heavy paper sheet provided with a top flap overlying a corresponding portion of at least one of said sheets and provided with a plurality of spaced holes, said one sheet bearing contrasting sections appearing through said holes when said sheets are properly aligned in said holder.

aligned in said holder, each of said contrasting sections being of substantially the same size and shape as its corresponding hole; and a transfer means between said sheets.

7. A bookkeeping device comprising a first record sheet having a vertical row of spaced holes at each side margin with each lateral pair of holes being located at the ends of a section on said sheet adapted to receive writing and bearing indicia at one end of said section; a second record sheet having similarly spaced sections bearing indicia on each end of said section so that the indicia are visible through said holes when the first sheet is placed over the second sheet to permit alignment of a given section on one sheet with a given section on the other sheet preparatory to making entries in said sections; and a holder in which said superposed sheets are held to maintain said alignment, said holder comprising a heavy paper sheet provided with a top flap and at least one side flap embracing and overlying corresponding edge portions of said superposed sheets, the flaps being of narrow width so as not to interfere with the making of entries on said record sheets.

8. A bookkeeping device comprising a first record sheet having a vertical row of spaced holes at each side margin with each lateral pair of holes being located at the ends of a section on said sheet adapted to receive writing and bearing indicia at one end of said section; a second record sheet having similarly spaced sections bearing indicia on each end of said section

so that the indicia are visible through said holes when the first sheet is placed over the second sheet to permit alignment of a given section on one sheet with a given section on the other sheet preparatory to making entries in said sections; and a holder in which said superposed sheets are held to maintain said alignment, said holder comprising a heavy paper sheet provided with a side flap embracing and overlying corresponding portions of said sheets and provided with a row of holes spaced similarly to the holes in said first sheet for alignment with said first sheet holes and through which said indicia on said second sheet appear when said sheets are properly aligned and arranged in said holder, said indicia on said first sheet being located beyond said side flap.
